FEEDER FOR GRANULAR MATERIALS

Eugene A. Wahl, 294 Forest Ave., Glen Ridge, N.J.

Filed Oct. 19, 1961, Ser. No. 67,161

Term of patent 14 years

(CL. D55—1)

T25309

Des. 197,734

PAGE 2

FIG. 5

FIGURE 1 is a front view of a feeder for granular materials embodying my new design;

FIGURE 2 is a similar view but taken from the left side;

FIGURE 3 is a similar view but taken from the right side;

FIGURE 4 is a similar view taken from the rear; and

FIGURE 5 is a top plan view thereof.
The dominant features of my design reside in the portions shown in full lines.

I claim:

The ornamental design for a feeder for granular materials, as shown and described.
